UNITED STATES PATENT OFFICE

159,930

AUTOMOTIVE VEHICLE STEERING WHEEL AND HORN RING ASSEMBLY

Arthur Ross, Detroit, Mich., assignor to General
Motors Corporation, Detroit, Mich., a corpora-
tion of Delaware

Application January 20, 1950, Serial No. 7,367

Term of patent 7 years

(Cl. D14—30)

To all whom it may concern:

Be it known that I, Arthur Ross, a citizen of the United States, being a resident of Detroit, State of Michigan, have invented a new, original, and ornamental Design for an Automotive Vehicle Steering Wheel and Horn Ring Assembly, of which the following is a specification, reference being made to the accompanying drawing, forming a part thereof.

In the drawing:

Figure 1 is a plan view of an automotive vehicle steering wheel and horn ring assembly showing my new design.

Figure 2 is a sectional view thereof taken substantially on line 2—2 of Figure 1.

Figure 3 is a detail sectional view taken on line 3—3 of Figure 1.

I claim:

The ornamental design for an automotive vehicle steering wheel and horn ring assembly, substantially as shown.

ARTHUR ROSS.
